SERVO-MECHANISM

Herbert C. Edwards, Detroit, Mich., assignor to
Packard Motor Car Company, Detroit, Mich., a
corporation of Michigan

Original application March 31, 1932, Serial No.
602,233. Divided and this application August
7, 1933, Serial No. 683,976

9 Claims. (Cl. 121—41)

This invention relates to control mechanism and more particularly to mechanism of the servo type, this application being a division of my application Serial No. 602,233, filed March 31, 1932.

5 An object of this invention is to provide a new and novel form of servo-mechanism which is sensitive and manually controllable within small limits of movement.

Another object of the invention is to provide a 10 control mechanism in which hydraulic servo-mechanism can be selectively connected or disconnected so that either manual or hydraulic means can be employed to actuate the same.

A further object of the invention is to provide 15 an improved form of hydraulic control mechanism.

Other objects of the invention will appear 20 from the following description taken in connection with the drawings, which form a part of this specification, and in which:

Fig. 1 is a sectional view of a device incorporating the invention;

Fig. 2 is a sectional view through the servo-mechanism taken on line 2—2 of Fig. 1;

25 Fig. 3 is another sectional view of the servo-mechanism taken on line 3—3 of Fig. 1;

Fig. 4 is still another sectional view of the servo-mechanism taken on line 4—4 of Fig. 1;

Fig. 5 is an elevational view of the device;

30 Fig. 6 is a sectional view of the device taken on line 6—6 of Fig. 1;

Fig. 7 is a longitudinal section of the plunger forming a part of the servo-device taken on line 7—7 of Fig. 3;

35 Fig. 8 is another longitudinal section of the plunger of the servo-device taken on line 8—8 of Fig. 3;

Fig. 9 is a sectional view of a fragment of the servo-device taken on line 9—9 of Fig. 5;

40 Fig. 10 is a plan view, partly in section, of the control means for the servo-mechanism and one of the actuators operated thereby;

Referring now to the drawings by characters of reference, 66 represents an actuator element, for 45 adjusting mechanism to regulate fuel injections for engines, upon which is fixed a rack member 70 which meshes with a gear segment fixed on a yoke 71 mounted on a shaft 72. 30 represents another actuator for adjusting mechanism to 50 regulate air supplied to engines and between such actuators I provide connecting means so that they can be operated by mechanism of the servo type which is manually controlled.

The servo-mechanism is mounted upon a support 55 65 and is connected with a source of fluid

under pressure. A housing or cylinder 80 is secured to the support 65 and is provided with an oil inlet port 81 which is connected with a pressure system by means of a conduit 82 provided in the bracket 83. The engine lubricating system is arranged to lead into the passage 84 in the support, for example, as shown in the application of Lionel M. Woolson, filed April 4, 1930, Serial No. 441,390, and an outlet 85 is provided in the cylinder through which oil returns to the lubricating system. 5

Within the cylinder is arranged a plunger element consisting of a central body portion 86 and two end portions 87 and 88, the end portion 88 being formed with a sleeve 89 which extends 15 through the bearing 90 at one end of the cylinder. Another sleeve 91 is arranged to telescope into the sleeve 89 and threaded therein is a shaft 92 which extends into the cylinder and through the piston structure. The other end of this shaft 20 92 has an extension 93, detachably secured therewith, which is arranged to slide through a bearing 94 formed on one end of the cylinder. Within the last mentioned bearing is a packing ring 95 which is compressed by a nut 96 screwed into 25 the end of the bearing, such nut being hollow so that the shaft extension 93 can slide therein. The purpose of the shaft extension 93 and its arrangement with the packing is to provide 30 resistance to free movement of the shaft 92 in the cylinder. The piston sections are secured together by a plurality of axially extending bolts, as indicated at 97. Each end of the central section 86 of the piston structure is formed with a 35 pair of separate chambers which extend in a plane transversely to the piston axis, one of the chambers 98 at each end of the piston serves as an inlet while the other chamber 99, at each end of the piston, serves as an outlet. Extending in an axial direction through each of the end sections of the piston is a port 100 which is arranged to establish open communication between the outlet chamber 99 and the end of the cylinder. 40

The piston end sections are also provided with 45 suitable rings, as indicated at 102, to prevent leakage around the cylinder engaging portion thereof. The central section of the piston structure is formed with a pair of saw-cuts forming chambers 103 which extend into the periphery a 50 short distance in spaced relation axially and which slightly overlie each other axially of the piston so that they each communicate with a longitudinally extending recess 104 formed in the central piston section and extending axially 55

thereof, this recess being arranged so that it communicates with the outlet port 85 in the cylinder and chambers 103 being arranged so that they each communicate with an outlet chamber 99. 5 The central portion of the piston is also formed with a similar pair of saw-cuts in the periphery thereof, opposite the saw-cuts 103, forming chambers 105 which are in spaced relation axially of the piston and in open communication with a recess 106 which extends in an axial direction along the periphery of the central section of the piston. The recess 106 is arranged to register with the inlet port 81 in the cylinder, and the chambers 105 are in open communication with the chambers 98. 10

Valves, as indicated at 106', are arranged to co-operate with seats 107 in order to control the passage of fluid between the chambers 98 and 106, such valves extending in opposite directions. 20 Another pair of valves 108 are arranged to co-operate with seats 109 formed in the central piston section in order to control flow of fluid between the outlet chambers 103 and 99. 25

The valve position is controlled by the rod 92 and on such rod I provide arms 110 and 111 which are located in recesses formed in the piston so that they can reciprocate with the shaft 92. The arm 110 is provided with adjustable tappets 112 which are arranged to align with the ends of the 30 pair of valves associated with the opposite end of the piston and the arm 111 carries adjustable tappets 113 which are arranged to align with the valve ends 108 and 106' for the other end of the piston structure. Surrounding each of the 35 valve stem ends is a coil spring 114 which seats at one end against the piston and at the other end engages a retainer 115 fixed adjacent the end of each of the stems, such springs normally tending to move the valves into a closed position 40 with their seats. The tappets are set close to the valve ends so that a very short movement of the rod and arms is required in order to open the valves. In order that the rod 91 can be actuated to move the piston structure manually, I provide 45 shoulders 116 with which the arms 111 and 112 engage upon a short movement of the rod 91.

The outlet chamber 99 at each end of the piston structure communicates with the inlet chamber at the opposite end of the piston structure 50 through means of axially extending passages 117 extending through the central piston section and surrounding two of the bolts 97.

A bearing 120 extends through the crank case 10 and is clamped to the crank case by a nut 121. 55 Projecting through the bearing is a sleeve 122 and carried by the sleeve is the shaft 72. To the outer end of the shaft is fixed an arm 124 having an end 125 to which suitable mechanism, as indicated at 125', can be fixed for rotating the arm 60 from a remote location. Both the shaft 72 and the sleeve 122 are freely rotatable relatively, and relative to the bearing 120. The yoke member 71 is formed at one end with tongues 126 which extend into complementary recesses in the inner end 65 of the sleeve 122.

The shaft 92 is threaded into the sleeve 91 and projects beyond the end thereof, such sleeve being also telescoped within the sleeve 89 and projecting beyond its end. A pin 127 extends through 70 the projecting end of the sleeve 91 and pivotally mounted on such pin is a link 128. The other end of this link extends between the arms of a yoke 129, which is pressed onto the end of shaft 72, and the link 128 and yoke 129 are pivotally 75 connected by the pin 130. The arms of the yoke

71 have pivot members 131 extending therethrough and pivotally mounted on such pivot members is a U-shaped link 132. Threaded upon the projecting end of the sleeve 89 is an extension 133 pivoted on the pins 131 carried by one end of the sides of the link 132. The other end of the sides of the arms of the link 132 are mounted upon pins 135 which are fixed to arms 136 projecting from the gear segment yoke 71. 5

The arm 124 is arranged with relation to the engine so that the forward or rearward movement of the extended operating mechanism associated therewith will cause rotation of the shaft 72. Such movement of the shaft 72 will rotate therewith 10 the yoke 129 which in turn will impart movement to the link 128 which is transmitted through the pin 127 to reciprocate the sleeve 91, and as this sleeve is fixed to the shaft 92, the arms 110 and 111 will be moved in an axial direction in the cylinder 80. 15

When the shaft 92 is moved toward the bottom end of the cylinder, as shown in Figs. 1 and 6, the tappets 112 on the arm 110 will engage the stem ends of the valves 106' and 108 at the upper end of the piston and will move them toward the bottom end of the cylinder establishing communication between the lower inlet chamber 105 and the adjacent chamber 98. Oil from the pressure system will thus be free to move through the port 81 in the cylinder, the open inlet chamber 105 and into the chamber 98. Such oil flow passes from the chamber 98 axially of the piston through the port 117 and into the upper exhaust chamber 99 from which it flows through the port 100 into the upper end of the cylinder and thereby exerts a downward pressure against the piston causing it to move with the rod 91 toward the bottom of the cylinder. While the lower inlet valve 106' is thus held open, the outlet valve at the lower end of the piston is also held open and fluid in the bottom end of the cylinder can flow through the port 103 and the outlet chambers 99 and 103 and thence into the recess 104 and through the outlet port 85 in the cylinder. The outlet port 85 opens directly into the crank case and the oil drops to the bottom thereof along with that which has escaped from the bearings within the crank case and is recirculated in the system in the usual manner. The port 81 is always in open communication with the system through conduit means previously described so that whenever either one of the inlet valves 106' is open, oil from the system is free to flow into one or the other end of the cylinder because the inlet passages 105 are always in communication with the port 81 through the axially extending recess 106 formed in the periphery of the piston. The exhaust port 85 is always in open communication with the outlet chambers 103 even though they are in different axial planes for the reason that there is a space between the cylinder wall and the chambers 103 formed by the recess 104 and whenever the valves 108 are open, there will be a flow from one end or the other of the cylinder through the port 85. 40 45 50 55 60 65

Upward movement of the shaft 92 will open the valves at the upper end of the piston and similar flow of fluid will pass through the cylinder and the piston structure in a similar but reverse manner as that just previously described. In this 70 manner, rotation of the shaft 72 will take only sufficient energy to move the arms 110 or 111 into a relation opening the adjacent valves, whereupon there will be a corresponding movement of the piston effected by the system so that very 75

little manual effort is required in order to move the piston within the cylinder. Friction of the bearing member 95 against the shaft extension 93 is sufficient to keep the regulating mechanism in a definite relation with the servo device, thus preventing creeping of the members 30 and 66 in any adjusted position due to engine vibration. The tappets 112 and 113 are adjusted so that very little movement of the bars 110 and 111 is required in order to open the associated valves which also tends to decrease the amount of manual effort required before the hydraulic or servo-action takes place.

When starting the engine, there is of course no pressure in the system and hand operation of the mechanism is resisted by the high vacuum in the cylinder. In order to overcome this resistance to manual operation of the mechanism, I provide the passage 140 which extends substantially normal to and in communication with the passage 82 in the supporting bracket 83, and into the outer end of this passage 140 I provide an air inlet cap 141. A one way ball valve 142 is arranged within the inlet member 141 and is normally held to close the port 143 by means of a spring 144. When there is pressure in the passage 82, it will maintain the valve 142 in closed position so that there can be no entrance of air, but when there is a vacuum in the cylinder, then air is free to flow into the cylinder and thereby reduces the vacuum so that vacuum resistance to manual operation is substantially reduced.

As the sleeve 89 is formed as an integral part of an end section of the piston, it will reciprocate with the piston and in so doing will impart similar movement to the yoke extension 133 and through means of the pins 131, this motion being transmitted to the link 132 which transmits rotation to the gear segment yoke 71 through the pin connections 135. Rotation of the gear yoke 71 is imparted to the rack 70 which is fixed to the ring 66 and is also imparted to the sleeve 122 through means of the association of tongues 126 with the recesses in the sleeve.

It will thus be seen that the sleeve 122 and the ring 66 are both responsive to reciprocatory movement of the piston. Occasionally it is desirable to move the actuator 66 faster than the servo-mechanism will operate and, under such circumstances, the fast movement of the rod 92 will cause the one or the other of the arms 110 or 111 to engage against the adjacent shoulder 116 formed of the piston structure, depending upon the direction of the shaft movement, and such engagement will allow the piston to be moved manually as quickly as may be desired. It will therefore be seen that, in case of emergency or when desired, adjustment of the actuators 66 and 30 can be made manually. The sleeve 122 is rotated with the gear segment yoke 71 and carried by the outer end of the sleeve is a roller 145 which is located to engage in a recess 146 formed in an arm 147 fixed to a rotatable support 20. An arm 32 is fixed on the rotatable sleeve 20 and has a ball shaped end 149 engaging in a socket formed in an arm 31 on a hub 33 which is fixed to the actuator 30. It will therefore be seen that rotation of the sleeve 122 will rock the roller 145 which engages with the arm 147 and rotates the associated support 20 so that the arm 32 associated therewith will move the actuator 30. Thus rotation of the gear yoke 71 and the sleeve 122 occur simultaneously so

that the actuators 66 and 30 will be moved together.

The control mechanism described is compact and sensitive and can be actuated manually or hydraulically at will.

Although the invention has been described in connection with a specific embodiment, the principles involved are susceptible of numerous other applications which will readily occur to persons skilled in the art. The invention is therefore to be limited only as indicated by the scope of the appended claims.

What I claim is:

1. In a servo-mechanism, a cylinder having fluid inlet and outlet ports in the wall thereof, a piston in the cylinder composed of three axially arranged sections having bolts for securing the same together, the central section of the piston having an enlarged passage around two of the bolts, a pair of peripheral recesses extending the length of the central section and communicating one with the cylinder inlet port and the other with the cylinder outlet port, a pair of chambers extending normal to the axis of the central piston portion through each recessed portion of the outlet recess periphery, axially extending openings in each of the end piston sections each communicating with one of the chambers communicating with the valve means in the piston controlling the passage of fluid between the outlet chambers and the openings in the end sections, manually operable means for controlling the position of the valve means, the chambers communicating with the inlet recess each being in communication with the openings in the remote end sections through means of the enlarged passages around the bolts, and actuator means connected with the piston and extending exteriorly of the cylinder.

2. In a servo-mechanism, a cylinder having fluid inlet and outlet ports in the peripheral wall thereof, a piston in the cylinder, the central portion of the piston having two axially extending passages therein, a pair of peripheral recesses extending axially of the central portion of the piston and in open communication one with the cylinder inlet port and the other with the cylinder outlet port, axially spaced pairs of chambers extending transversely in the piston and communicating with the peripheral recesses, axially extending openings in each end of the piston communicating with the chambers, valve means in the piston controlling the passage of fluid between the chambers and the openings in the end portions of the piston, manually operable means for controlling the position of the valve means, the chambers communicating with the inlet recess in the piston each being in communication with the openings in the remote end portion of the piston through means of the axial passages in the central portion of the piston, and actuator means connected with the piston and extending exteriorly of the cylinder.

3. A servo-mechanism comprising a cylinder having fluid inlet and outlet openings through the peripheral wall thereof, a piston reciprocable in the cylinder having a peripheral recess communicating with the inlet opening and another peripheral recess communicating with the outlet opening, a pair of chambers extending in a transverse plane adjacent each end of and within the piston, one of each pair of chambers communicating with one piston recess and the other of each pair of chambers communicating with the other piston recess, passages connecting one

of the chambers at each end of the piston with the inlet opening and the other chamber at each end of the piston with the outlet opening, valve means for closing the junctions between the 5 chambers and the passages, axially extending openings connecting the inlet chambers with the outlet chambers, axial passages leading from the chambers through the adjacent head ends of the piston, manually operable means extending into the cylinder for regulating the position of the 10 valves, and actuator means connected with the piston and extending axially of the cylinder.

4. A servo-mechanism comprising a cylinder having fluid inlet and outlet openings through 15 its peripheral wall; a piston in the cylinder formed of three aligned sections, said middle section having peripheral recesses communicating with the inlet and outlet openings, a pair of transversely extending chambers in each end, 20 connecting passages between a chamber at each end and the inlet recess and between the other chamber at each end and the outlet recess, connecting passages between the inlet and outlet chambers at opposite ends of the section, said 25 piston end sections having axially extending openings therethrough communicating one with each adjacent chamber; valve means normally closing the chambers from the connecting passages; manually operable means for opening said 30 valves; and actuator means connected to be operated by the piston.

5. A servo-mechanism comprising a cylinder having fluid inlet and outlet openings through the 35 peripheral wall thereof, a piston reciprocable in the cylinder having a pair of peripheral recesses one communicating with the inlet openings and the other communicating with the outlet openings, a pair of chambers in the piston adjacent each end thereof, one chamber of each pair communicating with the inlet recess and the other chambers communicating with the outlet recess, 40 passages connecting one of the chambers at each end of the piston with the inlet opening and the other chamber at each end of the piston with the outlet opening, valve means normally closing the 45 junctions between the chambers and the passages, axially extending openings connecting the inlet chambers at one end with the outlet chambers at the other end of the piston, axially extending passages leading from the chambers through the adjacent head end of the piston, manually operable means extending into the cylinder for selectively opening the valves at either 50 end thereof and actuator means connected with the piston and extending exteriorly of the cylinder.

6. A servo-mechanism comprising a cylinder having fluid inlet and outlet openings through the 60 peripheral wall thereof; a piston in the cylinder, an intermediate portion of said piston having peripheral recesses communicating with the inlet and outlet openings, a pair of transversely extending chambers in each end, connecting passages between a chamber at each end and the 65 inlet recess and between the other chamber at each end and the outlet recess, and connecting passages between the inlet and outlet chambers at opposite ends of the piston, the end portions of said piston having axially extending openings therethrough communicating one with each 70 chamber; spring seated valve means in the piston normally closing each chamber from the passage connected therewith; a manually operable rod extending into the piston and having a pair of arms fixed thereon for selective opening engage- 75

ment with the valves at either end of the piston; and actuator means connected to be operated by the piston.

7. A servo-mechanism comprising a cylinder having fluid inlet and outlet openings through the peripheral wall, a piston reciprocable in the cylinder having peripheral recesses communicating one with the inlet opening and the other with the outlet opening, a pair of chambers adjacent each end of and within the piston, passages connecting one of the chambers at each end of the piston with the inlet opening through the recess communicating therewith and the other at each end of the piston with the outlet opening through the recess communicating therewith, spring seated valves for closing the junctions between the chambers and the passages, axially extending openings in the piston connecting the inlet chambers at one end with the outlet chambers at the other end, axially extending passages extending from the chambers through the ends of the piston, a manually operable rod extending through the piston and having a pair of spaced arms fixed thereon for engaging the valves at either end of the piston to selectively unseat them, said arms abutting said piston after a predetermined movement relative thereto to manually operate the same, and actuator means connected with the piston and extending exteriorly of the cylinder. 30

8. A servo-mechanism comprising a cylinder having fluid inlet opening and a fluid outlet opening through the peripheral wall thereof, a piston reciprocable in the cylinder having a peripheral recess communicating with the inlet opening and another peripheral recess communicating with the outlet opening, a pair of chambers within the piston adjacent each end thereof, passages connecting one of the chambers at each end of the piston with the inlet opening through the peripheral recess associated therewith and passages connecting the other chambers at each end of the piston with the outlet opening through the peripheral recess associated therewith, spring seated valves for closing the 40 junctions between the chambers and the passages, axially extending openings connecting the inlet chambers with the outlet chambers, axially extending passages leading from the chambers through the ends of the piston, manually operable means extending through the piston for selectively operating the valves at either end thereof, said means after a limited movement relative to the piston engaging therewith to cause manual operation thereof, and actuator means connected with the piston and extending exteriorly of the cylinder. 45

9. A servo-mechanism comprising a cylinder having fluid inlet and outlet openings through the peripheral wall thereof, a piston reciprocable in the cylinder having a peripheral recess communicating with the inlet opening and another peripheral recess communicating with the outlet opening, a pair of chambers in the piston adjacent each end thereof, passages connecting one of the chambers at each end of the piston with the inlet opening through the recess associated therewith and the other passage at each end of the piston with the outlet opening through the recess associated therewith, spring seated valves for closing the junctions between the chambers and the passages, axially extending openings connecting the inlet chambers with the outlet chambers at opposite ends of the piston, axially extending passages leading from the chambers 65

through the ends of the piston, inwardly opening spring seated valve means associated with the inlet opening in the cylinder through which air automatically passes upon a drop of pres-

selectively opening the valves at either end of the piston, and actuator means connected with the piston and extending exteriorly of the cylinder.

5 sure below atmospheric in the cylinder, manually operable means extending into the cylinder for

HERBERT C. EDWARDS. 5

CERTIFICATE OF CORRECTION.

Patent No. 2,005,971.

June 25, 1935.

HERBERT C. EDWARDS.

It is hereby certified that error appears in the printed specification of the above numbered patent requiring correction as follows: Page 3, second column, line 26, claim 1, strike out the words "outlet recess" and insert the same before "valve" in line 29, of said claim; and that the said Letters Patent should be read with this correction therein that the same may conform to the record of the case in the Patent Office.

Signed and sealed this 13th day of August, A. D. 1935.

Leslie Frazer
